UNITED STATES PATENT OFFICE.

CHARLES HENRI CLAUDEL, OF LEVALLOIS-PERRET, FRANCE.

CARBURETER.

1,327,703.

Specification of Letters Patent. Patented Jan. 13, 1920.

Application filed January 26, 1914, Serial No. 814,403. Renewed October 21, 1919. Serial No. 332,330.

To all whom it may concern:

Be it known that I, CHARLES HENRI CLAUDEL, a citizen of the Republic of France, residing at Levallois-Perret, Seine, France, have invented new and useful Improvements in Carbureters, of which the following is a specification.

This invention relates to carbureters for use in internal combustion engines, and 10 more particularly to carbureters of the kind in which the control of the inlet for the air and the outlet for the combustible mixture is effected by a single controlling member which simultaneously governs the relative 15 value of the cross-sectional areas of these passages in the carbureter in accordance with the position to which the controlling member is adjusted.

The invention has for its object to improve the operation of carbureters of this 20 type and more particularly those comprising a regulating valve adapted to be oscillated or rotatably displaced for the purpose of governing the supply of combustible gas 25 to the engine. The invention is further particularly adapted to be applied in connection with carbureters of the well-known Claudel type in which the oscillating regulating valve performs the double function 30 of controlling the admission of combustible mixture to the engine, and of controlling the amount of air admitted to the carbureter.

In the accompanying drawings the invention is illustrated as embodied by way 35 of example in various improved constructions of carbureter of the Claudel type above referred to.

Figures 1, 2 and 3 are diagrammatic 40 views in sectional side elevation, sectional front elevation and plan respectively of a regulating valve of a carbureter embodying one form of the invention; Fig. 4 being a view similar to Fig. 2, but illustrating a 45 modified construction.

Figs. 5 and 6 illustrate the invention as applied to a recent type of Claudel carbureter, Fig. 5 being a view in sectional side elevation of the mixing chamber of the 50 carbureter and Fig. 6 a sectional plan view on the line 6—6 of Fig. 5.

Referring now to the drawings it will be seen from Figs. 1, 2 and 3, that the carbureter comprises in common with the earlier 55 types of Claudel carbureter a rotary con-

trolling valve *b* and a spraying nozzle *c* projecting within an opening in the controlling valve. The principal feature of the present invention consists in the provision of two partitions *d* arranged parallel 60 to the axis of the opening *a* and on each side of the spraying nozzle *c* in such a manner as to form an intermediate restricted chamber *D*. The function of the chamber *D* is to constitute a zone of relatively small 65 volume particularly when the controlling valve is in its nearly or partially closed position with the object of more or less confining the air to the region surrounding the nozzle *c*.

As shown in Fig. 4 which illustrates a construction in which hollow partitions are provided, the internal walls of the partitions *d* may be perforated so that the hollow interior of the partitions is in communication with the space *D*, passages *e* *e'* being provided communicating with the hollow partitions in all or certain positions of the regulating valve *b*, the passages *e* *e'* serving for the supply of cold or heated air 80 to the interior of the partitions, the air passing through the perforated walls of the partitions into the space *D* from which it escapes with the rest of the combustible mixture. The imperforate outer wall of 85 the hollow partition is designated by the letter *d* and the internal imperforate wall of the hollow partition is designated by the letter *d'*.

It will be understood that these partitions 90 are capable of being embodied in any type of carbureter comprising a carburation chamber interposed between the inlet and outlet of the carbureter, this carburation chamber being located either within an oscillating regulating valve of the Claudel 95 type or within any other form of regulating valve, although this feature is particularly useful in connection with oscillating regulating valves having an opening therein of cylindrical, conical or other form with 100 in which the spraying nozzle is located.

Referring now to Figs. 5 and 6, the carbureter is illustrated as having an oscillating regulating valve *b* with an opening 105 therein in the form of a truncated cone, the spraying nozzle being of the well-known Claudel type. The conical opening *a* of the regulating valve *b* is so arranged that its base or larger end is adjacent to the outlet 110

of the carbureter leading to the induction pipe of the engine for the purpose of facilitating the flow of the gaseous mixture.

The partitions *d* inclose as in the construction above described, a restricted carburation chamber *D* surrounding the upper portion of the spraying nozzle *c*. In Fig. 5 the top of the partition *d* is broken away. The spraying nozzle itself is in this case of improved construction being provided with inlet holes for air leading into the annular mixing chamber of the nozzle. All or certain of these air inlets are located at points at which the variable reduction of pressure due to the suction of the engine is different from the pressure obtaining at the outlet orifice *i* of the gaseous mixture.

For example, the air inlet orifices are shown in Fig. 5 as being arranged in two groups, viz—those indicated at *i*¹ which are located in the free path of the air or adjacent to the air inlet of the carbureter where the variation of pressure is very small, the other group of inlets, viz., those indicated at *i*², being located farther within the carbureter and therefore subjected to variations in pressure which are considerably greater than is the case at the inlets *i*¹.

As the regulating valve *b* of the carbureter is opened and in proportion to the amount of such opening and the consequent increase in speed of the engine, the drop of pressure at the inlets *i*² will increase and will counterbalance the drop of pressure occurring at the outlet orifice *i*.

This action will be more pronounced if, as in the construction illustrated in Fig. 5 the conical form of the opening in the regulating valve is continued throughout the inlet portion of the body of the carbureter to a sufficient extent to exert an influence upon the inlet orifices *i*².

The falls of pressure occurring at the orifices *i*¹, *i*², and at the orifice *i*, do not follow the same curve of variation and it is therefore possible to obtain a proper adjustment of the carburation under different running conditions of the engine and more particularly to obtain an automatic reduction in the richness of the gaseous mixture at high speeds.

It will be understood that the features of improvement in the spraying nozzle above described which constitutes a feature of the present invention can be applied to a carbureter having a regulating valve of any suitable type and may moreover be employed without necessarily utilizing the partitions *d* in the carburation chamber above referred to.

The improved form of spraying nozzle may also be employed in connection with carbureters having various relative arrangements of the nozzle and regulating valves other than those above referred to, the

spraying nozzle being not necessarily located within the interior of the regulating valve, but being otherwise arranged if desired. The improved spraying nozzle is in fact generally applicable to all carbureters in which one or more orifices are provided for discharging the liquid fuel into a current of air delivered to the main delivery pipe of the carbureter, the withdrawal of air from the suction column of the carbureter being partly or wholly due to the variations in pressure resulting from the suction of the engine.

The invention is evidently not limited to the improved constructions above described by way of example, which merely illustrate various arrangements embodying one or more features of the invention and the latter is accordingly only to be regarded as limited to the extent indicated by the appended claims.

I claim as my invention:

1. The combination in a carbureter of a rotatable valve having an opening therein constituting a mixing chamber, a fuel injection device extending into and located within said opening in said valve and means carried by the valve for preventing the expansion of the air in the mixing chamber in certain positions of the valve.

2. The combination in a carbureter of a rotatable member having an opening constituting a mixing chamber, said valve simultaneously controlling the supply of air to and the outlet of combustible mixture from the mixing chamber, a fuel injection device located within the mixing chamber, a partition located on each side of the nozzle, said partitions being within said valve and extending through said mixing chamber, and means for confining the passage of air between the partitions in certain positions of the valve.

3. The combination in a carbureter of a rotatable plug member controlling the supply of combustible fluid to the motor, a mixing chamber located within the interior of said rotatable member, a fuel injection nozzle projecting within said rotatable member, partitioning devices located on either side of the fuel injection nozzle and rotatable with said plug cock, means for insuring the passage of air between said partitioning devices and in the region of the fuel injection nozzle and an orifice for supplying a combustible mixture from a point in the carbureter distant from said fuel injection nozzle in accordance with the variation in the pressure at different points.

4. The combination in a carbureter of a regulating valve having a passage therethrough within which the fuel injection device is located, a plurality of partitions rotatable with said valve dividing said passage into a corresponding number of compart-

ments, one of which incloses said spraying nozzle in all positions of the valve and means for limiting the air passing through said valve to this compartment for certain positions of the regulating valve.

5. The combination in a carbureter of a rotatable plug cock having an opening therein constituting the mixing chamber, a fuel injection nozzle located within the interior of said mixing chamber, partitioning devices on either side of said fuel injection nozzle, means for causing the passage of air between said partitioning devices and adjacent to the outlet of said fuel injection nozzle in certain positions of the rotatable member means for supplying a combustible mixture at a point distant from the fuel injection nozzle, and means for causing the air employed for generating the additional supply of combustible mixture to traverse a sinuous path prior to its ultimate delivery.

6. The combination in a carbureter of a regulating valve having a passage therein constituting a mixing chamber, a fuel injection device, means for permitting the flow of air through said passage past said injection device, means carried by said valve for limiting said flow to a region closely adjacent to said injection device for certain positions of said valve, said regulating valve having passages outside of said mixing chamber for admitting a larger flow of air through the valve for certain positions of the valve.

35 7. The combination in a carbureter of a rotary plug cock having a passage therein constituting a mixing chamber, means constituted by the opposite faces of said valve for controlling the inlet of air and the outlet of combustible mixture from said chamber, a fuel injection device projecting within said chamber and means carried by said plug cock for limiting the flow of air through said chamber to a region closely adjacent to said fuel injection device for certain positions of said valve.

8. The combination in a carbureter of a rotary plug cock having a transverse passage therein constituting a mixing chamber, a fuel injection device projecting within said chamber, transverse partitions surrounding said fuel injection device and arranged at right angles to the axis of rotation of said cock to permit rotation of said cock without interfering with said injection device.

9. The combination in a carbureter of a rotatable controlling valve, a fuel injection nozzle located in a passage formed in the interior of said valve, means for restricting the volume of said mixing chamber in certain positions of the valve by reducing the width of said chamber in a direction parallel to the axis of rotation of said valve, a separate passage for supplying combustible mixture to the interior of the mixing chamber,

means for causing the air employed in generating said combustible mixture to follow a sinuous path prior to its ultimate delivery and means for varying the supply of combustible mixture from said second delivery nozzle in accordance with the variation of the pressures within the interior of the carbureter.

10. The combination in a carbureter of a regulating valve, a fuel injection device, means for dividing the interior of said valve into a plurality of compartments within one of which said injection device projects and means for varying the temperature of the interior of said compartment.

11. The combination in a carbureter of a rotatable plug cock controlling the supply of air to and the outlet of combustible mixture from a mixing chamber located within the interior of said plug cock, means for dividing the interior of said mixing chamber into a plurality of compartments and means for rendering the temperature of one of said compartments different from the remainder.

12. The combination in a carbureter of a regulating valve having an opening therein constituting a mixing chamber, a fuel injection device, partitions dividing said chamber into a plurality of compartments within one of which said injection device is located and means constituted by said partitions for varying the temperature of said mixing chamber.

13. The combination in a carbureter of a rotatable plug cock, a chamber within the interior of said plug cock constituting a mixing chamber, a fuel injection nozzle projecting within said mixing chamber, means for dividing the mixing chamber into a number of compartments, a number of concentrically arranged members surrounding the injection nozzle and means permitting the passage of air between said concentrically arranged members for generating a separate supply of combustible mixture.

14. The combination in a carbureter of a rotatable plug cock having an opening therein constituting a mixing chamber, a plurality of hollow partitions separating said chamber into a number of compartments, a fuel injection device located within one of said compartments and means for supplying heated fluid to the interior of said hollow partitions.

15. The combination in a carbureter of a main controlling valve, a fuel injection device having a main outlet adapted to supply a combustible liquid in substantially uniform quantities, an auxiliary outlet adapted to supply a combustible mixture in variable quantities, means for causing the combustible fluid supplied from the auxiliary source to traverse a sinuous path prior to its delivery to the carbureter and means

for automatically varying the amount of fluid thus supplied in accordance with the variation in the pressures at different points in the carbureter.

- 5 16. The combination in a carbureter of a fuel injection device having a main outlet for combustible liquid and an additional outlet for combustible fluid, means for admitting air to said injection device located
  - 10 at a point at which variations in pressure due to the suction of the engine are a minimum and means for admitting air to the injection device at a point at which the variations in pressure are greater than at the
  - 15 aforementioned point.
17. The combination in a carbureter, of a cylindrically formed rotatable plug which is provided with a through diametrical port,

spaced-apart plates for dividing said through port into two or more compartments, a wall for limiting the amount of the flow of fluid through some one of said compartments when the plug is in a predetermined or certain position, means for limiting the rotary movement of said plug and a fuel injection device having a plurality of intake openings and located within the last-mentioned compartment of said rotatable plug.

In testimony whereof I have signed my name to this specification in the presence of two subscribing witnesses.

CHARLES HENRI CLAUDEL.
